FLUORESCENT LAMP SOCKET CROWN

Frederick K. Maerz, New York, N. Y., assignor
to Harry J. Gruber and Max D. Gruber, doing
business as Gruber Bros., New York, N. Y.

Application February 13, 1939, Serial No. 256,153

3 Claims. (Cl. 173—328)

This invention relates to improvements in lamp socket caps.

Broadly, it is an object of my invention to produce a lamp socket cap which will cover the lamp socket and fit snugly and securely upon the lamp socket.

More particularly, it is an object of my invention to provide a lamp socket cap that will fit upon a lamp socket by frictional means so that the end of the lamp socket will be covered by an ornamental cap and will aid in keeping the lamp within the socket.

Another object of my invention is to provide a lamp socket cap particularly for fluorescent lamp sockets, the cap to be maintained in position upon a lamp socket by frictional means which is invisible when the cap is in position upon the socket.

Another object is to provide a lamp socket cap that can be economically manufactured, of neat appearance and readily removed and replaced when desired.

For a fuller understanding of the nature and objects of my invention, reference is had to the following detailed description in connection with the accompanying drawing, in which:

Fig. 1 is a plan view showing the inside of the lamp socket cap having a single teat projecting at right angles from said cap into a slot of a fluorescent lamp socket.

Fig. 2 is a plan view showing the inside of the lamp socket cap having a single teat projecting at an acute angle from said cap into a slot of a fluorescent lamp socket.

Fig. 3 is a plan view showing the inside of the lamp socket cap having double parallel teats projecting at acute angles from said cap into parallel slots of a fluorescent lamp socket.

Fig. 4 is a vertical section taken on line 4—4 of Fig. 5, showing the cap, part of the socket and part of the lamp.

Fig. 5 is an end elevation of the cap and part of the lamp socket showing the design and contour and revealing that various designs and ornamentation may be used.

Fig. 6 is a side elevation of the cap seated upon the lamp socket, showing part of said socket and part of the fluorescent lamp.

Referring to Fig. 1 of the drawing, numeral 10 represents a fluorescent lamp socket with a single vertical channel or slot 11 to receive the pin 12 of a fluorescent lamp 13, shown in Fig. 4.

The lamp socket cap 14 has a teat 15 projecting from flange 16 and base 17. The flange 16 has an opening 18 wide enough to permit entrance of the lamp socket 10 within the cap chamber

formed by the base 17 and the flange of the cap 14. The teat 15 is placed opposite opening 18 so that it will enter the channel 11 of the socket 10. The teat 15 is of sufficient width and thickness so that it will enter channel 11 and be held within the channel 11 by frictional engagement, thus holding cap 14 in position upon the socket 10.

The socket 10 has a cavity 19 in which are posts 20 having a central channel 21 and separating contact blades 22.

In placing the fluorescent lamp within socket 10, pin 12 (shown in Fig. 4) passes through socket channel 11 and central channel 21 so that pin 12 comes to rest against blades 22. The cap 14 is then placed over socket 10 acting as a cap or crown for the socket 10 and lamp 13.

In Fig. 2, there is a modified lamp socket 23, with a channel 24 placed at an angle. The cap 25 has a flange 26 at right angles to base 27. Flange 26 has an opening 28 to permit entrance 20 of the socket 23. A teat 29 projects from the flange 26 and base 27 at an acute angle and parallel to channel 24 of socket 23. The teat 29 is opposite opening 28 and the width of channel 24 so that it will enter channel 24 and be firmly held in frictional engagement within said channel. Within channel 24 there is a moveable contact blade 30 for pin 12 of the fluorescent lamp 13.

In Fig. 3 there is another modified lamp socket 31 having two channels 32 and 33 to receive the pins of a fluorescent lamp. Cap 34 is similar to cap 25 except that it has two projecting teats 35 and 36 instead of one. The teats 35 and 36 are parallel and project at acute angles from flange 37 and run parallel to channels 32 and 33. Channels 32 and 33 have moveable contact blades 38 and 39, respectively. Flange 37 has an opening 40 to permit entrance of the socket 31. Teats 35 and 36 are placed opposite opening 40 and are as wide as channels 32 and 33 so that they are held by frictional engagement within said channels.

It is obvious that various changes and modifications may be made in the details of construction without departing from the general spirit of the invention, as set forth in the appended claims.

I claim:

1. A lamp socket cap, comprising a base and a flange projecting from said base, an opening in said flange to receive a lamp socket, a teat depending from said flange opposite said opening for entrance into a slot of a socket and a space between said teat and said base.

2. A lamp socket cap, having a base, a flange at right angles to said base and substantially sur-

rounding said base, an opening in said flange for receiving a lamp socket, teats projecting from said base and flange opposite said opening for entrance into lamp socket slots, and a space between said teats and said base.

5. 3. In combination with a lamp socket, a cap having a base, a flange projecting from said base and disposed to one side thereof and at right angles thereto, an opening in said flange for en-

trance of said lamp socket, teats projecting from said flange opposite said opening, a space between said teats and said base, slots at the end of said lamp socket, said slots slightly larger in width than said teats and cooperating with said teats to 5 maintain said cap upon said lamp socket by frictional engagement.

FREDERICK K. MAERZ.
